UNITED STATES PATENT OFFICE.

GEORGE W. WOODWARD, OF BROOKLYN, ASSIGNOR TO THE ANSONIA BRASS
AND COPPER COMPANY, OF NEW YORK, N. Y.

LAMP.

SPECIFICATION forming part of Letters Patent No. 417,621, dated December 17, 1889.

Application filed July 5, 1889. Serial No. 316,552. (No model.)

To all whom it may concern:

Be it known that I, GEORGE W. WOODWARD, of Brooklyn, Kings county, and State of New York, have invented a certain new and useful Improvement in Lamps, of which the following is a specification.

I will describe a lamp embodying my improvement in detail, and then point out the novel features in claims.

10 In the accompanying drawings, Figure 1 is a partly-sectional side view of the lower part of a lamp embodying my improvement. Fig. 2 is a sectional elevation of the lower part of a lamp on a larger scale. Fig. 3 is a view 15 similar to Fig. 2, except that it shows certain parts in a different position and omits the reservoir. Fig. 4 is a section taken on the line $\alpha\alpha$, Fig. 2.

Similar letters of reference designate corresponding parts in all the figures.

A designates a support for a lamp-reservoir. As here shown, it forms a portion of a hanger or harp, and consists, essentially, of a bow-shaped lower portion a and two arms a' , 25 extending upwardly therefrom. It is provided with shoulders a^2 .

B designates the lamp-reservoir. It may be made of any suitable material. In the present instance it is represented as made of sheet 30 metal.

The support A and the reservoir B are provided with pins or projections and sockets which interlock to engage the reservoir with its support. In the present instance the pins 35 or projections a^3 are attached to or formed with the support A, and sockets b are attached to the reservoir. These sockets may be made of metal and secured by solder or other means to the reservoir when the latter is made of 40 metal. If the reservoir were made of other material—as, for instance, glass—the lugs might be formed integral with a ring receiving the reservoir. The sockets and pins or 45 projections may be disengaged, and the reservoir then moved out of its support by a horizontal movement.

There is combined with the support and reservoir a catch or lock for precluding any accidental upward movement of the reservoir 50 relatively to the support A. This catch or lock, as here shown, consists of a pin or bolt

C, fitted to move vertically in a socket b' , with which the part a of the support A is provided. A spring c coils around the pin or bolt C, and, bearing against a head at the lower end of the latter and the lower end of the socket, moves the pin or bolt downwardly and holds it normally in its lowest position. Above the socket b' is a bifurcate portion b^2 of the part a of the support. Within this 60 bifurcate portion are arranged tumblers or hooked plates c' . These are hung at the upper end on a pin c^2 , which passes through the bifurcate portion b^2 . The tumblers or hooked plates are adapted to swing in reverse 65 directions. Their hooked portions are on their outer edges. Near their lower ends there are oblique slots c^3 . The oblique slot of one tumbler or hooked plate extends in a reverse direction to that of the other. A pin 70 c^4 extends through the oblique slots c^3 , and is secured to the pin or bolt C. The upper end of the pin or bolt C is longitudinally slotted to fit the pin c^2 . By pressing the pin or bolt upwardly against the resistance of the spring 75 c , the pin c^4 , acting within the oblique slots c^3 , swings the tumblers or hooked plates inwardly, as may be understood by reference to Fig. 3. When the pin or bolt C moves downwardly, the pin c^4 , acting within the oblique 80 slots c^3 , swings the tumblers or hooked plates outwardly, as may be readily understood by reference to Fig. 2.

The reservoir B is provided on the under side with an extension B', having in it a central socket b^3 . This socket slips over the bifurcate portion b^2 of the support A and over the tumblers or hooked plates c' . When the reservoir is in place in the support A, the socket b^3 will be below the hooked portions of 90 the tumblers or plates c' and will be engaged thereby.

It will be seen that I prevent a lateral or horizontal displacement of the reservoir by means of the pins or projections and sockets a^3 b , and that I secure the reservoir against upward movement relatively to the support A by means of the catch or lock. To disengage the reservoir it is only necessary to press the pin or bolt C upwardly, and then lift the 100 reservoir slightly and subsequently to move it laterally or horizontally.

It is very desirable to be able to remove the reservoir without much upward movement, because when the upward movement is reduced the burner and chimney may the more readily be moved beyond the shade of the lamp and the support for the shade.

What I claim as my invention, and desire to secure by Letters Patent, is—

1. In a lamp, the combination, with a reservoir and a support therefor, of pins or projections and sockets whereby the reservoir and support may be engaged to prevent the horizontal movement of the one relatively to the other, and a catch or lock arranged beneath the reservoir for securing the reservoir and support against independent vertical movement, substantially as specified.

2. In a lamp, the combination, with a reservoir and a support therefor, of pins or projections and sockets whereby the reservoir and support may be engaged to prevent the horizontal movement of the one relatively to

the other, a catch or lock consisting of a bolt, and tumblers engaging with a socket, substantially as specified. 25

3. In a lamp, the combination, with a reservoir and a support therefor, of pins or projections and sockets whereby the reservoir and support may be engaged to prevent the horizontal movement of the one relatively to 30 the other, and a catch or lock consisting of a vertical bolt and horizontally-moving tumblers, substantially as specified.

4. In a lamp, the combination, with a reservoir and a support therefor, of a catch or lock consisting of a longitudinally-moving pin or bolt and tumblers or hooked plates moving transversely to said pin or bolt, substantially as specified. 35

GEORGE W. WOODWARD.
